ROTARY FORGE FURNACE

William M. Hepburn, Ottawa Hills, Ohio, and
 William O. Owen, Evanston, Ill., assignors to
 Surface Combustion Corporation, Toledo, Ohio,
 a corporation of Ohio

Application August 9, 1944, Serial No. 548,762

7 Claims. (Cl. 263—7)

1

The present invention relates to a combustion-heated rotary forge furnace for heating articles to forging temperature in a protective atmosphere and has for its object to provide an improved furnace of this type.

For a consideration of what is believed to be novel and our invention attention is directed to the following specification and the claims appended thereto.

In the accompanying drawings:

Fig. 1 is a vertical section through a rotary furnace embodying the present invention.

Fig. 2 is a reduced partial plan and horizontal section of the furnace shown in Fig. 1.

Fig. 3 is an enlarged vertical section of parts embodied in the furnace shown in Fig. 1.

Fig. 4 is a fragmentary vertical cross section of parts in Fig. 3.

Fig. 5 is a front elevation and Fig. 6 is a partial side elevation and vertical section of door operating mechanism embodied in the furnace shown in Fig. 1.

Fig. 7 is an enlarged horizontal cross section of parts of the door operating mechanism.

Figs. 8 to 10 are fragmentary detail views of parts embodied in the furnace shown in Fig. 1.

The improved furnace comprises a plurality of relatively elongated retorts or muffles 10 horizontally disposed about a vertical axis on a rotary support or platform 11 mounted for rotation about said axis by any preferred means shown as comprising a circular track 12 secured to the underside of the platform and supported on rollers 13 mounted on a foundation base 14. The platform is power driven by any preferred means shown as comprising a ring gear 15 or the like secured to the underside of the platform.

The platform constitutes the bottom of a combustion chamber heated by burners in burner ports 16. It is not essential that the upper half of the combustion chamber should rotate with the lower half and, therefore, to this end the upper half is made stationary and is comprised of a bell 18 having a flat roof 19 and a depending circular side wall 20 which terminates short of an upstanding circular side wall 21 constituting part of the platform 11.

The bell 18 is supported from above by a plurality of hangers 22 secured to side wall of the bell and extending upwardly to an overhead support 23 which in turn is supported on pedestals 24 extending upwardly from the fixed foundation of the furnace. To prevent undue leakage of combustion gases from the combustion chamber at the joint between the upper and lower

2

halves of said chamber, a peripheral liquid seal is provided at said joint, the seal being comprised of a circumferential trough 26 secured to the platform wall 21 and a circumferential flange 27 secured to the bell wall 20 for dipping into the trough 26. The lower edge of the bell wall 20 will ordinarily be water cooled by a cooling ring 28 embedded therein.

The retorts 10 are preferably but not necessarily so mounted on the platform 11 that the heating gases in the combustion chamber in order to pass out of said chamber must first flow under the retorts and thence into the foot of an upright exhaust flue 29 mounted on the platform 11 and from which they pass to waste by way of a communicating flue passage 30 in the roof of the bell 18. The flue passage beneath each retort is indicated at 31, and the gas entrance to this passage at 32.

At their inner ends the retorts 10 are disposed against an abutment 36 from which they extend forwardly to and through radial apertures in the upstanding side wall 21 of the platform 11. Between said abutment and said apertures the retorts are supported on saddles 38, and in said apertures they are surrounded by asbestos rope packing 39. The retorts must be able to withstand a forging temperature of 2300° F. and, therefore, are made of a non-metallic refractory

material such as silicon carbide (Carborundum) which has a high thermal conductivity (for a non-metallic refractory) and which retains great strength to compressive loads at elevated temperatures. The retorts are built up of circular

sections 40 arranged end to end in abutting relation and an end closure 41. A yieldable compressive force is applied to the outer end of the retort to hold the sections thereof in abutting relation so as to maintain the retort reasonably

gas-tight at its joints. This compressive force is applied by a plurality of springs 43 which press against a sleeve-type metal frame 42 which in turn presses against the outer end of the retort, the springs being held in place by bolts 44 carried by brackets 48 secured to the metal casing

49 of the wall 21 of the platform 11. The frame 42 has lateral lugs 37 through which said bolts extend. In order to maintain the frame 42 relatively cool there is embedded in the wall 21 a cooling ring 47 through which the sleeve portion of the frame extends. A door 45 cooperates with outer end of the frame to close the retort.

The work to be heated in the retort is supported on a flat hearth 50 comprised of a series 55 of flat top stools 51 which have depending end

walls with arcuate bottoms for proper seating in the retort. The end walls of the stools are apertured or notched as at 53 so that a work-protecting atmosphere, such as nitrogen, from a feed chamber 55 at the lower front end of the retort may flow beneath the hearth to the rear end of the retort and thence upwardly whereby to insure proper distribution of the atmosphere throughout the retort. The atmosphere is supplied to the chamber 55 by an upright pipe 54 which constitutes part of a pipe 56 which leads from a supply chamber 57 co-axial with the platform 11 therebelow. The main supply pipe leading to this chamber 57 is indicated at 58.

When a retort is at the charging station it is desirable to provide for a greater inflow of protective atmosphere than is normally required once the retort has been thoroughly purged of air. To this end the pipe 54 is provided with a flapper type valve 60 which when opened permits increased flow of protective atmosphere to the retort. To open the valve, the flapper has a downwardly extending operating arm 61, the free end of which carries a roller 64. Normally the center of gravity through the arm and roller is such as to hold the flapper in closed position. One or more bleed holes 63 in the flapper permits a minimum flow through the valve when the flapper is in closed position. To turn the flapper to open position there is provided in the path of the roller 64 a cam track 62 having at its front end an incline up which the roller must ride. The track is long enough to hold the valve open for some time after the retorts move away from charging position.

The charging station is indicated at 65 and the discharging station at 67, it being understood that the rotation of the platform on which the retorts are supported is clockwise as viewed in Fig. 2. At the charging station is a door operating means 66 and at the discharging station is an identical means 66'. This door operating means comprises an elevator 68 adapted to be actuated by means under the control of the operator. The elevator comprises a cross head 69 (see Fig. 5) confined to vertical movement by vertical guide ways 71. On top of the cross head is a saddle 72 adapted to interengage with an overhead cross bar 73 carried by rigid arms 74 depending from the door 45. The door is supported by means 46 comprising axially aligned journal pins 75 at the lateral sides of the door, these pins extending into a cam slot 76 in guide plates 77 carried by the spring pressed frame 42. The cam slot comprises an upper inverted V-shape portion 78 for guiding the door into wedging position against the outer face of the spring pressed frame 42. It will, therefore, be understood that to open the door it is first moved upwardly and then downwardly by the elevator means and that the reverse movement will close the door. When the weight of the door is taken by the saddle 72 the door can fulcrum about its cross bar 73 and the guide pins 75 can, therefore, pass from one leg to the other of the cam portion 78 during the operation of opening and closing the door.

In the operation of the furnace it will be obvious that the turnable support 11 on which the retorts or muffles are mounted will be periodically turned to bring one retort after another to the loading station for loading and that by the time the first loaded retort again reaches the loading station the work therein will have been heated to forging temperature in a protective atmosphere

and removed therefrom at the station immediately preceding the loading station.

The use of a plurality of relatively small individual retorts mounted for turning in unison about a common vertical axis in a common combustion chamber makes it unnecessary to shut down the furnace for immediate repairs simply because one retort may be in need of repairs and, of course, makes it possible to adjust the individual atmosphere requirements of each retort to maintain a protective atmosphere about the work therein. Moreover, by maintaining the retorts under compression, it becomes practical to employ preformed readily replaceable sections of heat conducting non-metallic refractory in the construction of the retorts.

By supporting the closure doors for the retorts in a manner permitting the use of power operated door operating means at the loading and unloading stations for opening and closing the doors, the loading and unloading operations can proceed with minimum delay.

The provision of means for automatically increasing the flow of protective atmosphere to a retort that has just been loaded reduces to a minimum the danger of damage to the work by oxidation immediately following loading.

Other advantages of the present invention will be apparent to those skilled in the art. The apparatus is relatively simple and is easily kept in repair.

What is claimed as new is:

1. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, a station where the articles to be heated are placed in the retorts and another station where the heated articles are removed from the retorts, and means for conducting an article protecting atmosphere to said retorts during their course of travel about said vertical axis.

2. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, a station where the articles to be heated are placed in the retorts and another station where the heated articles are removed from the retorts, and means at said stations for opening and closing the doors of the retorts on their arrival at said stations.

3. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, a station where the articles to be heated are placed in the retorts and another station where the heated arti-

cles are removed from the retorts, and means for conducting an article protecting atmosphere to said retorts during their course of travel about said vertical axis, said retorts comprising individual sections arranged end to end, and means for maintaining the retorts under longitudinal compression to maintain them relatively gas-tight at their joints.

4. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, a station where the articles to be heated are placed in the retorts and another station where the heated articles are removed from the retorts, means for conducting an article protecting atmosphere to said retorts during their course of travel about said vertical axis, and means for temporarily increasing the input of said atmosphere to a retort following the charging thereof with articles to be heated.

5. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, said retorts being circular in cross section, and means providing a flat hearth in the retorts.

6. A rotary furnace comprising, in combination, a support mounted to turn about a vertical axis and having an upstanding peripheral wall, a plurality of retorts mounted on said support for rotation therewith and each having an access door at the outer side of said wall, means comprising said support and its upstanding wall forming a combustion chamber about said retorts for heating the retorts to heat the articles therein to elevated temperature, a station where the articles to be heated are placed in the retorts and another station where the heated articles are removed from the retorts, means for conducting an article protecting atmosphere to said retorts during their course of travel about said vertical axis, and means for temporarily increasing the input of said atmosphere to a retort following the charging thereof with articles to be heated.

7. A rotary furnace comprising, in combination, a support mounted for rotation about a vertical axis and having an upstanding peripheral wall, a plurality of cylindrical retorts mounted on said support and extending radially outward into individual apertures in said wall for rotation therewith, means comprising said support and its upstanding peripheral wall forming a combustion chamber about said retorts for heating them to heat the articles therein to elevated temperature, a sleeve means in said apertures to abut the adjacent end of the retort, means for yieldably pressing said sleeve means against the said end of the retort, and a door carried by said sleeve means for closing the access opening to the retort.
